UNITED STATES PATENT OFFICE.

JOHN W. LAKE, OF DALLAS, AND JAMES R. CHESNUT, OF FORT WORTH, TEXAS.

DESIGN FOR AN AUTOMOBILE-RADIATOR CAP.

57,677.

Specification for Design.

Patented Apr. 26, 1921.

Application filed September 7, 1920. Serial No. 408,787. Term of patent 7 years.

To all whom it may concern:

Be it known that we, JOHN W. LAKE and JAMES R. CHESNUT, citizens of the United States, residing, respectively, at Dallas, Dallas county, Texas, and Fort Worth, Tarrant county, Texas, have invented a new, original, and ornamental Design for Automobile-Radiator Caps, of which the following is a specification, reference being had to the accompanying drawing, forming part thereof.

The figure is a perspective view of an automobile radiator cap showing our new design.

We claim:

The ornamental design for an automobile radiator cap as shown.

JOHN W. LAKE.
JAMES R. CHESNUT.
